UNITED STATES PATENT OFFICE.

WILLIAM FERGUSON, OF CHICAGO, ILLINOIS.

FENCE-POST.

SPECIFICATION forming part of Letters Patent No. 761,291, dated May 31, 1904.

Application filed March 5, 1904. Serial No. 196,731. (No model.)

To all whom it may concern:

Be it known that I, WILLIAM FERGUSON, a citizen of the United States, residing at Chicago, in the county of Cook and State of Illinois, have invented a new, useful, and Improved Fence-Post, of which the following is a full, clear, and exact description, reference being had to the accompanying drawings, forming a part of this specification, in which the corresponding letters of reference in the different figures indicate like parts.

The primary object of my invention is to provide an improved fence-post formed from a plastic material and suitably reinforced by means of metal reinforcements arranged longitudinally thereof and having anchor elements embedded therein in such a way as not to project from the surface of the post, while being readily accessible for the fastening of fence-wires thereto by means of a fastening adapted to be disconnected therefrom or replaced when necessary, all of which is hereinafter more particularly described, and definitely pointed out in the claim.

In the drawings, Figure 1 is a front elevation of a fence-post embodying the features of my invention. Fig. 2 is a like view showing the usual wires attached thereto. Fig. 3 is a horizontal sectional view in plan, taken upon the line 3, Fig. 1; and Fig. 4 is a vertical sectional view taken upon the line 4, Fig. 1, viewed in the direction of the arrow there shown.

Referring to the drawings, *a*, Figs. 1 to 4, inclusive, represents my improved post, which is formed from concrete or other suitable plastic material, the body thereof being reinforced by means of one or more, but preferably four, steel or iron rods, cables, or heavy wires *b*, embedded therein throughout or substantially throughout its length, as indicated in Figs. 3 and 4. Said post is also provided upon one or more of its faces with a series of depressions or recesses *c* for the reception of anchor-bars *d*, which are arranged transversely of said post in such a way as to extend across said recess, a portion of said bar being exposed, while the ends thereof are embedded in the concrete, as clearly shown in Figs. 3 and 4. The bar *d* thus forms an an-

chor or fastening, to which a wire *e*, forming a part of the fence, may readily be attached by means of a link *f*, formed by inserting within the depression an ordinary U-shaped staple and bending the inner ends around the anchor-bar, in the manner shown in Fig. 4, which may readily be accomplished by means of suitable pliers. Said anchor-bar consists, preferably, of a straight piece of galvanized iron or steel, although it is obvious that it may be of any desired length and bent in any form, the only essential requisite being that it shall be sufficiently embedded in the concrete to form a secure anchorage. The advantages of such a construction are that the post presents no projecting metal parts to be bent or broken or to interfere with its shipment, while it enables the fence to be readily and firmly secured thereto in a cheap and simple manner. Moreover, it is obvious that the fastening may be replaced at any time. I prefer to make said post square in cross-section, with chamfered corners, although it is obvious that said shape may be varied indefinitely without varying from the principle of my invention.

Having thus described my invention, I claim—

As an improved article of manufacture, a fence-post formed from plastic material having a series of recesses therein disposed at predetermined distances apart, and a corresponding series of anchor-bars permanently embedded within said post in position to substantially parallel the fence-wires to be secured thereto, said bars being arranged to cross the chambers formed by said recesses whereby a portion of said anchor-bars may be exposed to secure a fastening thereto, while lying in a plane beneath the surface or outer face of the post.

In testimony whereof I have signed this specification, in the presence of two subscribing witnesses, this 29th day of February, 1904.

WILLIAM FERGUSON.
